UNITED STATES PATENT OFFICE

115,560

DESIGN FOR A CARRYING CASE FOR TYPEWRITERS

Johannes Krüger, Erfurt, Germany, assignor to Olympia Büromaschinenwerke A. G., Erfurt,
Germany, a corporation of Germany

Application February 14, 1939, Serial No. 82,986
In Germany May 13, 1938

Term of patent 14 years

To all whom it may concern:

Be it known that I, Johannes Krüger, a citizen of the German Reich, residing at Erfurt, Germany, have invented a new, original, and ornamental Design for a Carrying Case for Typewriters, of which the following is a specification, reference being had to the accompanying drawing, forming part thereof, and wherein,

Fig. 1 is a perspective view of a carrying case for typewriters showing my new design, and

Fig. 2 is a side elevation thereof.

The dominant features of my design reside in the portion shown in full lines.

I claim:

The ornamental design for a carrying case for typewriters, as shown and described.

JOHANNES KRÜGER.
